UNITED STATES PATENT OFFICE.

MARCYAN KARPOWICZ, OF BRIDGEPORT, CONNECTICUT.

RAILWAY-TIE.

1,152,417.

Specification of Letters Patent. Patented Sept. 7, 1915.

Application filed July 12, 1915. Serial No. 39,352.

To all whom it may concern:

Be it known that I, MARCYAN KARPOWICZ, subject of the Czar of Russia, residing at Bridgeport, in the county of Fairfield and 5 State of Connecticut, have invented certain new and useful Improvements in Railway-Ties, of which the following is a specification.

This invention relates to certain new and 10 useful improvements in railway ties.

The primary object of the invention is the provision of a tie for railway rails which is 15 adjustably positioned for employment with different sized rails, the tie being of such construction as to interfere with the free use of the roadbed by pedestrians when the ties are operatively positioned.

A further object of the device is the provision of a tie formed of any desirable material such as wood or concrete and presenting a sharpened upper edge when operatively positioned in its binding connection between the track rails and thereby serviceable as a cattle guard as well as assisting in preventing 25 the use of the railroad track as a walk for pedestrians.

A still further object of the device is to provide a tie having a plurality of supporting bases operatively positioned and thereby 30 positioning the rail engaging means at the required height for attachment with different sized rails.

With these general objects in view and others that will appear as the nature of the 35 invention is better understood, the same consists in the novel combination and arrangement of parts hereinafter more fully described, illustrated in the accompanying drawings, and pointed out in the appended 40 claims.

In the drawings forming a part of this application and in which like-designating characters refer to corresponding parts throughout the several views, Figure 1 is a 45 central vertical longitudinal sectional view through the device operatively engaging the opposite rails shown in vertical section. Fig. 2 is a top plan view of a track section partially broken away and showing three of 50 the present form of ties in position and Fig. 3 is a vertical transverse sectional view through the tie operatively positioned.

Referring more in detail to the drawings, 55 two rails 10 are herein illustrated arranged in parallelism in their track formation, the present form of tie being shown in connec-

tion therewith in the formation of the railroad track.

The tie member consists of a beam or girder 11 triangular in cross-section when 60 formed of any desired material such as wood or concrete and adapted for positioning between the rails 10 and arranged perpendicularly thereto and having its opposite ends engaging the inner faces of the base 65 flanges 12 of the rails.

The tie 11 is provided with passages 13, 14 and 15 which are arranged longitudinally extending through the said tie and adjacent the three edges 16, 17 and 18 thereof.

A binding rod 19 is adapted to be positioned through the desired passage of the tie 11 and has its opposite ends extending through perforations 20 arranged substantially central of the webs 21 of the rails. A 75 spacing sleeve 22 is carried by the rod 19 between the rail webs 21 and the adjacent ends of the tie 11, while lock nuts 23 are screw-threaded upon the opposite free ends of the rod 19, thus firmly securing the tie 80 and sleeves and rails together.

The present tie is made adaptable for different heights of rails, which it will be understood will thereby have their web perforations 23 arranged at different heights 85 and this is accomplished by having the tie passages of different distances from the opposite face or operative base of the tie. In other words, the passage 13 is of less distance from the opposite base face 24 of the 90 tie which face lies opposite the edge 16 thereof, while the passage 14 is at a greater distance from its base face 25 lying opposite the edge 17 and the passage 15 is a still greater distance from its base face 26, and 95 lies opposite the third edge 18 of the tie.

With the tie positioned upon the base 24 thereof, the tie will be serviceable in connection with rails having their web perforations 20 of a certain height above the foundation for the rails and tie while the tie will be positioned for rails of greater dimensions when the tie is seated upon its base 26 and the rod 18 extends through the tie passage 15 and positions the said rod at a 100 greater height from the supporting road bed such as 27 and in position to be secured through the central perforations of the web of the rails which the tie connects.

It will be also noted that either of the 110 bases 24, 25 and 26 may be employed when desired with any size of rails some of these

arrangements however positioning the base above or below the lower supporting surface of the rails. It is also noted that the passages 13, 14 and 15 lying at different distances from the operable base face of the tie are at different distances from the adjacent edges 16, 17 and 18 respectively of the tie.

A serviceable tie is thus provided which is cheap and easy to manufacture, but which at 10 the same time constitutes an adequate securing means for the rails in forming the track and the tie is adjustable for different sizes of rails.

While the form of the invention herein 15 shown and described is what is believed to be the preferred embodiment thereof, it is nevertheless to be understood that minor changes may be made therein without departing from the spirit and scope of the invention as set forth in the claims.

What I claim as new is:—

1. A railway tie triangular in cross section and provided with passages therethrough adjacent the three edges of the tie 25 and at different distances from the triangular opposite base faces of the tie, a binding rod positioned through the upwardly arranged one of said passages when the tie is operatively positioned, and rail-engaging 30 means at the opposite ends of the said rod.

2. A device of the class described comprising in combination with railroad rails

having opposite perforations through the webs thereof, a tie beam triangular in cross section perpendicularly arranged between 35 the said rails in engagement with the base flanges thereof, the said tie being provided with a longitudinal passage therethrough adjacent its upper edge, a tie rod positioned through the said passage and extending 40 through the said web perforations, spacing sleeves upon the said rod between the webs of the said rails and the adjacent ends of the said tie and lock nuts secured upon the outer ends of the said rod.

3. A device of the class described comprising in combination with opposite rails having registering perforations through the webs thereof, a tie triangular in cross section and having a longitudinal passage 50 therethrough adjacent and at different distances from each of the three corners thereof, a tie rod positioned through one of the said passages having its opposite ends secured through the said web perforations, 55 and spacing collars between the webs of the said rails and the adjacent end of the said tie.

In testimony whereof I affix my signature in presence of two witnesses.

MARCYAN KARPOWICZ.
